BOSTON, MASSACHUSETTS, A CORPORATION OF MAINE.

BLINDSTITCH SEWING-MACHINE.

1,273,855.

Specification of Letters Patent. Patented July 30, 1918.

Application filed May 2, 1916. Serial No. 94,986.

To all whom it may concern:

Be it known that we, THOMAS J. HAYES, a citizen of the United States, residing at Roslindale, county of Suffolk, State of Massachusetts, and HARLEY C. MOULTON, a citizen of the United States, residing at Dorchester, county of Suffolk, State of Massachusetts, have invented an Improvement in Blindstitch Sewing-Machines, of which the following description, in connection with the accompanying drawing, is a specification, like characters on the drawing representing like parts.

This invention relates to the stitch-forming mechanism of sewing machines and more particularly to that type of sewing machine in which the complementary elements of the stitch-forming mechanism are located both at the same side of the work.

The invention particularly relates to that type of mechanism in which a curved needle is employed and a complementary stitch-forming mechanism in which the loop taker is of the rotary or revolving hook type, although it will be obvious that as to certain features of the invention it is immaterial whether the loop taker rotates or oscillates, or whether it is of the hook type. One object of the invention is to enable the loop of needle thread to be entered with certainty by the beak of the loop taker. This is particularly desirable in machines such as that illustrated wherein the needle has a shogging or laterally vibrated movement, thus requiring the beak to enter the loop of needle thread in two different and more or less widely separated positions.

Another object of the invention is to cause the pull on the thread in setting the stitch to take place substantially in line with the path of the needle or the plane of the work and thus minimize the tendency of the beak to lift the work from off the work support.

Another object of the invention is to provide a novel relative arrangement of curved needle and complementary loop taker to enable the parts to occupy a compact space and yet secure the stitch-forming functions in an efficient manner. This is accomplished in the present invention by arranging the parts so that the needle passes outside of

or across the face of the beak of the loop taker and further by arranging the parts so that the axis of the loop taker shaft is substantially normal to a tangent to the path of the needle at the loop taking point.

Another object of the invention is to provide the loop taker, and when employed, its inclosed bobbin case and bobbin with a casing presenting a smooth exterior lower surface and preferably forming a substantial continuation of the presser foot so that the work may be fed beneath and past the presser foot and loop taker without contacting with the stitch forming mechanism except at the stitching point.

Another object of the invention is to provide for proper illumination of the work at the stitching point notwithstanding the location of the complementary stitch forming mechanism in the rear of the stitching point and close to the work.

Another object of the invention is to provide a construction of the character set forth in which ready access may be had to the loop taker for the removal and replacement of the thread supply.

These and other objects of the invention will appear more fully from the accompanying description and drawings, and will be particularly pointed out in the claims.

In the drawings,

Figure 1 represents a front elevation partially in vertical cross-section of the forward end of the overhanging arm and bed plate of a blind-stitch sewing machine of the Arbetter type embodying one form of the present invention;

Fig. 2 is an end elevation partially in vertical cross-section of the construction shown in Fig. 1;

Fig. 3 is a top plan view enlarged of the presser foot and bobbin case forming a part of the machine;

Fig. 4 is an end elevation with some of the parts removed and broken away of the forward end of the overhanging arm and bed plate of a blind stitch sewing machine of a different type embodying another form of the present invention;

Fig. 5 is a detail in front elevation of the presser foot, loop taker and casing shown in Fig. 4;

Fig. 6 is a plan view partially in cross-section taken on the line 6—6, Fig. 4;

Fig. 7 is a bottom plan view of the loop taker, casing and portion of the presser foot 5 with the casing cover shown open.

The invention is herein shown as embodied in a blind-stitch sewing machine and designed for felling, but it is obvious that in many of its features the invention is 10 not limited to a particular type of sewing machine. Only so much of the machine is illustrated as is necessary to an understanding of the present invention.

In Figs. 1 to 3 inclusive the invention is 15 shown in one form embodied in a blind stitch sewing machine of the Arbetter type and in the remaining figures is shown in another and improved form embodied in a machine of the general type shown in the 20 patent to Hayes No. 1,131,373 granted March 9, 1915.

Referring first to the construction illustrated in Figs. 1 to 3 inclusive, the bed plate 1 and the overhanging arm 2 are shown 25 broken away so that only the forward portion of each is shown. The vertically movable work support 3 which characterizes the Arbetter type of machine and the bender 4 for forming a bend in the work for the passage of the needle are shown as to their 30 effective portions, but as they are not particularly involved with the present invention the means by which they are operated are omitted. The presser-foot 5 is rigidly 35 secured at 6 to the post 7 depending from the head 8 of the overhanging arm and is formed in a suitable manner as shown in Fig. 3 to receive the bender to guide the needle and to guide the pieces of work to be stitched 40 together all in a manner well known and familiar.

In this blind-stitch type of machine the 45 stitch-forming mechanism is located entirely at one side of the work and in the form illustrated at the upper side of the work so that the thread is carried by the needle into and out of the same side of the work and is interlocked by the second thread also on the 50 same side so that the stitching may not appear upon the opposite side of the work. A curved needle is employed because greater accuracy of stitching, a finer class of work and more satisfactory results are secured. A shogging or laterally vibrated movement of 55 the needle is also desirable in the uniting of two or more layers of work in felling or padding. This requires that the needle shall coöperate in two quite widely separated points with the complementary instrumental- 60 ity such as the thread carrying rotary hook. These and the other requirements of the sewing machine render the construction and location of the complementary parts of the 65 stitch-forming mechanism a somewhat complicated problem.

In the construction illustrated the curved needle 9 is mounted on a needle carrier 10 having an extended bearing in a hub 11 of the vertical rocker 12. A link 13 connects a crank 14 on the needle carrier to an eccentric 15 on the main shaft 16 extending through the overhanging arm so that the needle is given thereby a reciprocating or oscillating movement to carry the thread into and out of the work. The oscillation or lateral vibration of the needle whereby it makes two or more rows of stitches is secured by the oscillation of the rocker 12 from the main shaft in a manner well known to those familiar with the Arbetter machine. 70 75 80

The complementary mechanism which co-operating with the needle forms the stitch is shown as a rotary or revolving hook with a contained bobbin case and bobbin of the general character of the Wheeler & Wilson 85 hook. In this invention the hook is so mounted that when the beak of the hook seizes the loop of thread thrown out by the needle the needle is then passing outside of or past the face of the hook with its path 90 substantially parallel to the face of the hook. This is secured by having the hook shaft and consequently the axis of rotation of the hook projecting upwardly in a line substantially 95 normal to a tangent to the path of the needle at the loop taking point. It is meant by the word "substantially" to allow some variation in either direction from a true normal or right-angled position because within a reasonable deviation therefrom the advantage of 100 the invention may be secured. In the drawing the axis of the hook is for this reason shown slightly deviating from the normal or rectangular relation. The hook shaft, of course, must not be tipped too far in an opposite direction from the normal to that 105 shown in Fig. 2 or the cast-off action of the hook might be interfered with. The limit in this direction will depend upon the construction and shape of the hook and its cast-off surfaces. 110

In the construction illustrated the hook shaft 17 is mounted in bearings suitably formed in the head of the overhanging arm and carries at its upper end a bevel gear 18 meshing directly with a coöoperating bevel gear 19 mounted on the main driving shaft 16. At its lower end the shaft 17 carries the hook 20 provided with the beak 21 and a cast-off shoulder 22 to insure the needle thread 115 being properly cast off as required by this type of hook. The inclosed bobbin case 23 containing the bobbin 24 is preferably seated to travel in the hook interior in the manner familiar to the Wheeler & Wilson type of hook, and is held from rotation by a projection 25 extending from the bobbin case and loosely engaging a recess 26 in the presser-foot. The bobbin case is provided with an aperture 27 the purpose of which is to allow 120 125 130

the hook to be placed as close as possible to the needle. The point of the needle in its forward thrust enters this aperture, but of course does not contact with the thread on 5 the bobbin, and this aperture is of sufficient width to receive the needle end or point in its different paths when laterally vibrated.

It will now be seen that the needle passes beneath or across the face of the beak of the 10 hook and when the beak enters the loop of thread thrown out by the needle the path of the needle at that point is substantially parallel to the face of the hook. This insures the pull on the thread in setting the 15 stitch taking place in a direction generally parallel with the work so that there is little tendency to draw the work up through the presser-foot and the stitch is properly tightened. This relation of the hook and 20 the needle or complementary parts of the stitch-forming mechanism also gives a wide range within which the beak of the hook may enter the loop thrown out by the needle, because it will be seen that in whatever position 25 the needle may lie by reason of a shogging or lateral vibration the beak of the hook will still be moving at the loop-taking point substantially parallel to the path of the needle, and so will be in practically no 30 danger of failing to enter the loop by reason of the height of the loop. But the length of the loop thrown out by the needle is considerable so that the beak of the hook has a 35 considerable range in the line of the seam within which it may enter the loop and as it is moving along the arc of a circle substantially at right angles to the path of the needle it varies in distance along the path of the needle but slightly.

40 Again it is to be noted that by positioning the parts as described the beak may be brought down at or near the face of the hook and the needle allowed to enter the bobbin case thus insuring a comparatively short 45 needle which is desirable for strength and accuracy in stitching.

In the construction illustrated suitable clearance is provided for the passage of the needle back of the point of the beak of the 50 hook by cutting away the beak slightly on its lower surface as may be seen in Fig. 2 of the drawing.

The driving connection for the hook simplifies and cheapens the construction, renders unnecessary any movement of the hook or its shaft bodily out of position, and yet allows the bobbin to be readily removed from the bobbin case because there is nothing to interfere with its removal owing to 60 the position of the hook.

The second form of the invention is shown in Figs. 4 to 7 inclusive and involves certain additional features which may also be embodied in the type of machine already described. In this latter form the blind-stitch

sewing machine illustrated is shown as of the general type illustrated in the aforesaid patent to Hayes No. 1,131,373 wherein the needle carrier 28 with its curved needle 29 is pivotally mounted to the bar 30 projecting downwardly from an overhanging arm on an axis 31 extending transversely at an oblique angle so that the oscillations of the needle take place in planes obliquely inclined to the surface of the work. The oscillation of the needle is effected by a link 32 in a generally similar manner as in the Arbetter type of machine already described and the needle may be moved bodily laterally to produce laterally separated rows of 80 stitches by any suitable means such, for example, as illustrated in the aforesaid patent to Hayes.

A casing 33 projects downwardly from the overhanging arm in the rear of the needle and serves to inclose the rotary loop taker and its driving shaft. This casing may be cast integral with the overhanging arm and may also project upwardly in the interior of the overhanging arm at 34 to form a 85 further bearing for the shaft. The rotary loop taker is illustrated as of the same general form as that already described in connection with the previous construction. As shown it is of the Wheeler & Wilson type 90 of rotary hook with a contained bobbin case and bobbin. The hook shaft 35 carries at its upper end a beveled gear 36 meshing directly with a coöperating beveled gear 37 mounted on the main driving shaft 38 of 100 the machine. At its lower end the shaft 35 carries the hook 39 provided with a beak 40 and cast off shoulder 41; and the inclosed bobbin case 42 and bobbin 43 with the aperture 44 in the bobbin case and projection 45 therefrom to engage loosely the presser foot, are and may be all substantially of the construction already described.

The casing 33 is provided with a cover 46 and completely incloses the loop taker excepting at the front where proper opening is left to enable the coöperation of the needle and loop taker. In the construction illustrated this casing at the front of the loop taker is faced off vertically at both sides of the front opening and the presser-foot 47 is secured directly thereto, the upwardly projecting lugs 48 of the presser foot being secured to the casing by the set screws 49. The presser-foot is thus rigidly and firmly held in position against the pressure of the work which in the case of these machines is given from below.

As in the case of the construction previously described the presser-foot extends 125 rearwardly at 50 beneath the path of the beak 40 of the loop taker and is provided with a recess 51 to receive loosely the projection 45 from the bobbin case.

The presser foot as herein illustrated has 130

its lower or work contacting surface 52 at an oblique angle to the horizontal and the yielding work support 53 has its work contacting surface correspondingly formed. 5 This feature forms no part of the present invention but is used in practice to affect the desired angle between the plane of the work and the plane of oscillation of the needle.

The feeding mechanism comprises a suitable feed dog 54 but as the means for operating it are not involved in the present invention they are not illustrated nor described. The work is also presented at the stitching point when required by a bender 15 55 which is operated at the required intervals to force the work up through an aperture in the presser-foot into the path of the curved needle, but again as the operating mechanism for the bender is not involved in 20 the present invention it is not illustrated nor described.

The cover 46 of the hook casing is shown as comprising an outwardly convex disk 56 with an upwardly projecting ring extending 25 around substantially the rear half of the hook, the remaining half being formed by the integral front portion of the casing. This cover is removable in order to enable access to be had to the hook for the removal 30 and replacement of the bobbin and bobbin casing. To secure this end the cover in the construction illustrated is shown as pivoted at 57, and provided with a snap catch 58 so that it may be swung to one side on the pivot 35 exposing the hook and inclosed bobbin and bobbin case. The disk 56 of the cover extends completely beneath the hook excepting that portion which is protected by the rearward extension 50 of the presser-foot. This 40 extension fits in a recess 59 formed in the cover for that purpose.

On its under surface the cover is preferably finished off smooth and as the lower surface of the presser-foot is smooth, and as 45 the cover and presser-foot form substantially one continuous surface it will be observed that as the work is fed along beneath the stitch-forming mechanism the work is protected at all times from contact with any 50 part of the stitch-forming mechanism, either the needle or the hook, except, of course, at the stitching point where the presser-foot is apertured for that purpose. This enables the work to be handled easily and rapidly 55 by the operator, to be guided and turned as required, and without any danger of interfering with the proper operation of the stitch-forming mechanism, and without any danger of the work being injured by coming 60 in contact with the hook or needle, except at the proper point.

By the location of the stitch-forming mechanism immediately above the work and in the general horizontal relation required 65 by this invention, that is, with the hook axis

substantially normal to the work, more or less of a shadow is cast upon the work at the stitching point by the mechanism of the machine. To obviate any objection from this source the invention provides for a proper illumination of the work at the stitching point. This result is secured by providing light admitting openings 60 in the upstanding periphery of the casing cover. The inner surface of the cover is polished or otherwise finished to reflect light while the lower surface of the hook and bobbin casing is also as usual of a highly polished character. The light, therefore, passes within the casing and is reflected back and forth out of the opening at the front of the casing directly onto the work at the stitching point.

The present invention has been described with respect to both types of machines, particularly in connection with the rotary or revolving hook of the Wheeler & Wilson type, but it is obvious from the explanation of the principles of the invention that it is not to be restricted to this particular type of complementary loop taker. The character of movement of the loop taker whether rotary or oscillating, whether of uniform or variable speed; the structural principle of the loop taker; the method by which the loop taker co-operates with the needle thread 90 whether by casting off as in the hook type or by passing bodily through the loop of needle thread as in the shuttle type are all immaterial so far as the broader aspects of this invention are concerned.

It will also be understood that the construction of hook, casing and presser-foot illustrated and described in connection with Figs. 4 to 7 inclusive is not to be limited to its use in the particular type of machine 105 illustrated in these figures but that the improvements described are equally applicable to the Arbette type of machine or to other types of blind stitch sewing machines.

This application is a continuation in part 110 of application No. 864,709 filed October 3, 1914, the constructions illustrated in Figs. 1 to 3 inclusive of the present drawings being precisely the same as in the aforesaid application.

Having fully described our invention, what we claim as new and desire to secure by Letters Patent is:

1. A sewing machine comprising in combination a curved needle, means for oscillating it about its axis of curvature, a rotary hook having its axis located substantially normal to a tangent to the path of the needle at the loop-taking point, and a bobbin case inclosed in said hook and provided with an aperture in its wall to receive the end of the needle upon its forward oscillation.

2. A sewing machine comprising in combination a curved needle, means for oscillating it about its axis of curvature, a rotary

hook having its axis located substantially normal to a tangent to the path of the needle at the loop-taking point, a presser-foot, and a bobbin case inclosed in said hook and having a projection extending therefrom and loosely engaging with the presser-foot to prevent rotation of the bobbin case while allowing the passage of the loop of needle thread therearound.

10 3. A blind-stitch sewing machine comprising a curved needle and means for oscillating it, a presser-foot rigidly located with respect to the path of the needle and acting to guide the needle in its oscillation, a complementary rotary thread carrying hook having its axis located substantially normal to a tangent to the path of the needle at the loop-taking point, a bobbin case inclosed in said hook, and means for loosely connecting 15 the bobbin case and presser-foot to prevent rotation of the former.

4. A sewing machine comprising in combination a curved needle, means for oscillating the needle about its axis of curvature, and means for laterally vibrating the needle, a rotary hook having its axis located substantially normal to a tangent to the path of the needle at the loop taking point, and a bobbin case inclosed in said hook and provided with an aperture in its wall to receive 20 the end of the needle upon its forward oscillation in any of its paths of lateral vibration.

5. A sewing machine comprising in combination a curved needle, means for oscillating it about its axis of curvature, a rotary loop taker having its axis located substantially normal to the path of the needle at the loop taking point, and a thread supply 25 carried by the loop taker and about which the needle thread is carried by the loop taker in the formation of the stitch.

6. A sewing machine comprising in combination a curved needle, means for oscillating it about its axis of curvature, a rotary loop taker having its axis located substantially normal to a tangent to the path of the needle at the loop taking point, a casing for 30 said loop taker extending beneath said loop taker, and means for feeding the work past said needle and beneath said casing.

7. A sewing machine comprising in combination a curved needle, means for oscillating it about its axis of curvature, a rotary loop taker having its axis located substantially normal to a tangent to the path of the needle at the loop taking point, a casing for 35 said loop taker extending beneath said loop taker, said casing being open in front to permit the coöperation of the needle and loop taker and being provided about its periphery with light admitting openings whereby the light may pass therethrough and then

through the front opening onto the work at the stitching point.

8. A sewing machine comprising in combination a curved needle, means for oscillating it about its axis of curvature, a rotary loop taker having its axis located substantially normal to a tangent to the path of the needle at the loop taking point, a casing for 40 said loop taker extending beneath said loop taker, the portion of said casing extending beneath the loop taker being separable from the remainder of the casing whereby access may be had to the loop taker.

9. A sewing machine comprising in combination a curved needle, means for oscillating it about its axis of curvature, a rotary hook having its axis located substantially 45 normal to a tangent to the path of the needle at the loop taking point, a bobbin case inclosed in said hook and provided with a thread supply, a casing for said hook extending beneath said hook, the portion of 50 said casing extending beneath the hook being separable from the remainder of the casing whereby access may be had to the bobbin case and thread supply.

10. A sewing machine comprising in combination a curved needle, means for oscillating it about its axis of curvature, a rotary loop taker having its axis located substantially normal to a tangent to the path of the needle at the loop taking point, a presser-foot 55 extending beneath the path of the beak of the loop taker, a casing for said loop taker extending beneath said loop taker and forming a substantial continuation of the presser-foot, and means for feeding the work beneath and past the needle, presser-foot and casing whereby the work is protected at all times from contact with the loop taker and needle except at the stitching point.

11. A sewing machine comprising in combination an overhanging arm, a needle supporting bar projecting downwardly from said arm, a curved needle mounted on said bar, means for oscillating the needle about 60 its axis of curvature, a casing projecting downwardly from said arm at the rear of the needle bar, a rotary hook and inclosed bobbin case located in said casing with the axis of rotation substantially normal to a 65 tangent to the path of the needle at the loop taking point, a presser-foot secured to and supported from the lower front face of said casing, a cover for and inclosing the bottom of the casing, and means for feeding the work beneath and past said presser-foot and casing cover.

In testimony whereof, we have signed our names to this specification.

THOMAS J. HAYES.
HARLEY C. MOULTON.
